UNITED STATES PATENT OFFICE.

GEORGE JOSEPH PATTON, OF NOKEVILLE, VIRGINIA.

BOOT OR SHOE VENTILATOR.

SPECIFICATION forming part of Letters Patent No. 752,254, dated February 16, 1904.

Application filed April 30, 1902. Serial No. 105,382. (No model.)

To all whom it may concern:

Be it known that I, GEORGE JOSEPH PATTON, a citizen of the United States, residing at Nokeville, in the county of Prince William and State of Virginia, have invented a new and useful Boot or Shoe Ventilator, of which the following is a specification.

This invention has for its object to provide for the ventilation of boots, shoes, or rubbers, more particularly of rubber boots, either while upon the foot or after the removal; and the invention consists in a ventilating-aperture in the toe or "upper" portion of the boot or shoe and having a movable water-tight closure.

The invention further consists in certain novel features of construction, as hereinafter shown and described, and specifically pointed out in the claim.

This invention is more particularly applicable to rubber and hunting boots, which are exposed to moisture and often immersed in water for hours at a time, and provides for the thorough ventilation of the interiors, especially of the remote parts of the foot or toe portions, to dry them out after such exposure.

In the drawings illustrative of the invention, Figure 1 represents a side view of the top portion of a shoe with the improved ventilating attachment applied thereto. Fig. 2 is an enlarged vertical section of the device attached to a shoe, the shoe portion being also shown in section. Fig. 3 is an enlarged plan view of the same.

The device will be attached to any portion of the upper of the boot or shoe, but preferably near the toe, and consists of a collar or sleeve 10, inserted into an aperture through the shoe (represented at 11) and secured therein preferably by flanging above and below the shoe material, as at 12 13, with a sheet-metal plate 14, secured by the flange 13 on the outside of the shoe.

The sleeve 10 will preferably be of metal, but may be of any suitable material and will be provided at its upper end with a cap or cover 15, as shown.

At one side the plate or frame 14 is provided with ears 16, adapted to engage a rectangular lever-frame 17, inclosing the sleeve 10, and

having a catch 18, adapted to engage a lug or stop 19 on the plate 14 opposite to the ears 16.

The lever-frame 17 is connected, as at 20 21, to the cap or cover 15 on opposite sides, as shown. The pressure of the rectangular frame 13 upon the cap or cover 15 will thus be distributed upon opposite sides, thus equalizing the pressure and forming a tight closure. By this means the cap 15 is secured in position upon the sleeve and adapted to be folded back to uncover the sleeve, as indicated in dotted lines in Fig. 2.

By connecting the cap 15 centrally at opposite sides it will be movable as upon trunnions upon the lever-frame and will be therefore free to adapt itself to its seat upon the sleeve and yield to any irregularity of surface thereon to insure a close joint between the parts.

A rubber or other suitable flexible packing will preferably be inserted between the closure 15 and the plate 14 to insure a water-tight joint. By this simple device an opening may be formed in the upper portion of the boot or shoe when required, either while on the foot or after its removal, whereby a thorough ventilation of the interior may be had, especially the remote portions, and thereby thoroughly dry them out after long exposure to moisture, and also to prevent undue perspiration as well as affording a means for the escape of moisture or other results of the perspiration of the foot.

The invention is especially valuable as applied to rubber and hunting boots, as before stated, which are frequently immersed for long periods of time in water and which it is very difficult to thoroughly dry out, especially in the remote portions of the toes. With my device applied thereto, however, an opening is provided near the toes, which may be closed water-tight when required and opened out when the boot or shoe is to be ventilated or dried out.

The aperture may be of any required size and the closure supported and actuated by any suitable means and may be modified and changed in minor details without departing from the spirit or sacrificing any of the advantages thereof.

Having thus described my invention, what claim is—

A ventilating device for boots and shoes, comprising a cylindrical tubular member extending through and connected with the upper, a base-plate adjacent to the outer side of the upper and having upturned ends, flanges upon the tubular member whereby the latter and the base-plate are connected with the upper, a cap forming a closure for the outer end of said tubular member, a rectangular frame connected hingedly with one upturned end of

the base-plate, pivotal connecting means between the sides of said rectangular frame and the cap, and means for connecting the free end of the rectangular frame with the opposite upturned end of the base-plate. 15

In testimony that I claim the foregoing as my own I have hereto affixed my signature in the presence of two witnesses.

GEORGE JOSEPH PATTON.
